(57) **CLAIM**

I claim the ornamental design for a golf bag stool, as shown and described.

DESCRIPTION

FIG. 1 herewith is a perspective view of the golf bag stool showing my design.

FIG. 2 herewith is a front elevation view of the golf bag stool of FIG. 1.

FIG. 3 herewith is a back elevation view of the golf bag stool of FIG. 1.

FIG. 4 herewith is a left elevation view of the golf bag stool of FIG. 1.

FIG. 5 herewith is a right elevation view of the golf bag stool of FIG. 1.

FIG. 6 herewith is a top view of the golf bag stool of FIG. 1; and,

FIG. 7 herewith is a bottom view of the golf bag stool of FIG. 1.

The broken and dotted lines shown in the figures depict environmental features that form no part of the claimed design.
